UNITED STATES PATENT OFFICE.

HENRY BROBERG, OF WARM SPRINGS, MONTANA.

RAIL-JOINT.

1,069,846.

Specification of Letters Patent. Patented Aug. 12, 1913.

Application filed April 12, 1912. Serial No. 690,353.

To all whom it may concern:

Be it known that I, HENRY BROBERG, a citizen of the United States, residing at Warm Springs, in the county of Deer Lodge 5 and State of Montana, have invented certain new and useful Improvements in Rail-Joints, of which the following is a specification.

This invention relates to improvements 10 in rail joints and its object is to produce a device of this class through the medium of which the adjacent ends of the rails in a stretch of track become interlocking, and the heads of the adjacent rail ends are beveled in the same direction, thus practically 15 making the track one continuous rail and avoiding the noise and jar incident to the wheel striking the ordinary straight rail head.

With the foregoing and other objects in view the invention consists in the combination and arrangement of parts to be herein-after fully described in the following specification, pointed out in the claim and illustrated in the accompanying drawings which 25 form a part of the specification and in which—

Figure 1 is a perspective view of a portion of a rail showing the splice-bar secured to 30 the web and provided with a cleat to be secured in the grooved base of the adjoining rail. Fig. 2 is an end view. Fig. 3 is a side elevation of the rail illustrated in Fig. 1. Fig. 4 is a side elevation of the rail to 35 be placed adjacent the one illustrated in Fig. 3. Figs. 5 and 6 are top plan views, respectively, of Figs. 3 and 4. Figs. 7 and 8 are inverted plan views of the same. Fig. 9 is a side elevation of two rails joined by my 40 improved joint. Fig. 10 is a bottom plan view of the same. Fig. 11 is a top plan. Fig. 12 is a section taken on line 3—3 of Fig. 11.

Like reference characters indicate corresponding parts throughout the several views. 45

Each end of each rail is provided with my improved joint which consists of a splice-bar 1 secured to or formed integral with the web 2 of the rail and projecting beyond the end of the rail and adapted to fit snugly 50 against the web of the adjoining rail to which it may be bolted if desired. The splice-bar 1 is provided with a transverse cleat 3 near its free extremity which cleat is adapted for insertion in a transverse 55 groove 4 formed in the base of each rail near each end. The cleats 3 are adapted to rest upon the ties to which they are spiked in the usual manner. The meeting ends of the rails provided with my improved joint are 60 beveled in the same direction as shown thus avoiding unnecessary jar in use. Each rail is provided with one of my improved joints at either end arranged on alternate sides.

What is claimed is:—

The combination of two rails, each rail having its base transversely recessed, a splice bar made integral with the web of each rail, each splice bar being projected beyond the head of its rail and disposed 70 upon the remote side of its rail web with relation to the other splice bar, a transverse apertured cleat carried at the free termination of each splice bar to engage the recessed portion of the adjacent rail base and 75 spikes for securing the said cleats to the rail ties.

In testimony that I claim the foregoing as my own I have hereto affixed my signature in the presence of two subscribing witnesses.

HENRY BROBERG.
